[57] CLAIM

The ornamental design for a gardening shear, substantially as shown and described.

DESCRIPTION

FIG. 1 is a front view of a gardening shear showing our new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a partial sectional view taken along the line 7—7 of FIG. 1;

FIG. 8 is a partial sectional view taken along the line 8—8 of FIG. 1;

FIG. 9 is a partial sectional view taken along the line 9—9 of FIG. 1;

FIG. 10 is a partial sectional view taken along the line 10—10 of FIG. 1;

FIG. 11 is a partial sectional view taken along the line 11—11 of FIG. 1;

FIG. 12 is a partial sectional view taken along the line 12—12 of FIG. 1; and

FIG. 13 is a front view of a gardening shear in the unlocked position.
